UNITED STATES PATENT OFFICE.

WALTER BELL HOPKINS, OF PROVIDENCE, RHODE ISLAND.

WATERPROOF ENTRANCE-BUSHING FOR WIRES.

SPECIFICATION forming part of Letters Patent No. 768,993, dated August 30, 1904.

Application filed December 22, 1903. Serial No. 186,177. (No model.)

To all whom it may concern:

Be it known that I, WALTER BELL HOPKINS, a citizen of the United States, and a resident of Providence, in the county of Providence and 5 State of Rhode Island, have invented a new and Improved Waterproof Entrance-Bushing for Wires, of which the following is a full, clear, and exact description.

My invention relates to waterproof entrance-bushings for wires—that is to say, to a device for running wires into buildings and closed spaces of various kinds without the possibility of water entering the conduits.

My invention also serves to prevent the 15 abrasion of the wires and is provided with means whereby it may be readily mounted upon poles, buildings, &c., whereby the wires may be readily placed in position.

Reference is to be had to the accompanying 20 drawings, forming a part of this specification, in which similar characters of reference indicate corresponding parts in all the figures.

Figure 1 is an elevation showing my invention as applied upon the exterior of a building. Fig. 2 is a vertical central section of the bushing and part of the conduit-pipe connected therewith, the view being taken upon the line 2 2 of Fig. 3; and Fig. 3 is a section upon the line 3 3 of Fig. 2 looking in the 30 direction of the arrow, the wires being removed.

Disposed adjacent to a building 1 is a pipe 2, threaded at its upper end, as shown in Fig. 2. The bushing consists of two parts—to wit, 35 a web 3 and a cap 4—these parts being secured together by means of a screw 5. The web 3 is provided with a collar 6, provided internally with a screw-thread 7, whereby it is secured upon the threaded end of the pipe 2, as 40 described. The web 3 is provided with apertures 8, through which wires 9 10 are threaded upwardly. The web is further provided with a somewhat larger aperture 11, through which the wires are threaded in the opposite direction, as indicated in Fig. 2. These apertures 45 are smooth, as indicated, and the surfaces immediately adjacent to the wire are preferably rounded, as indicated in Fig. 2. A bearing-block 12, integral with the cap 4, strengthens 50 the cap at that portion engaged by the screw

5 and enables the screw to obtain a secure grip thereupon. The collar 6 is provided with ears 13, each having a screw-hole 14 for the purpose of securing the collar 6 directly upon a building, thereby supporting the web 3, 55 which is integral with the collar, and the cap 4, which is secured thereto, as above stated.

With the construction above described it is impossible for water to enter the pipe 2 or any conduit or similar closure member connected therewith. The umbrella-like form of the cap causes the water to flow off readily, thus keeping the wires dry at the points where they pass through the web 3. It will be noted that the web 3 constitutes a bushing of a kind 60 which will meet the requirements of the various insurance associations, in that it makes such a connection with the wires as will not cause abrasion of the wires, and that it admits of being fastened to buildings and otherwise 65 complies with the various obvious requirements.

A fuse-box 15 is connected with the wires 16 17, leading directly into the building, and is of ordinary construction.

In order to assemble my apparatus, the cap 4 and the web 3 are secured rigidly together by means of the screw 5, as above described, and the collar 6 is then screwed upon the upper threaded end of the pipe 2, as indicated 80 in Fig. 2. The wires may be threaded through the apertures 8 and 11 either before or after the parts are assembled, as desired.

Having thus described my invention, I claim as new and desire to secure by Letters Patent— 85

1. As an article of manufacture, a waterproof entrance-bushing for wires, comprising a body portion provided with ears integral therewith, and also provided with apertures, said ears being provided with holes whereby 90 said body portion may be mounted, and means for connecting a cap upon said body portion for the purpose of protecting the same from the weather.

2. As an article of manufacture, a waterproof entrance-bushing for wires, comprising a body portion provided with ears integral therewith, whereby it may be secured upon a building, and also provided with a collar for engaging a pipe, said body portion being pro- 95 100

vided with apertures, one of them registering with said collar, and a cap for covering said body portion.

3. As an article of manufacture, a water-
5 proof entrance-bushing for wires, comprising
a web portion provided with ears, said web
portion being substantially circular in general
outline and provided with apertures, means
for fitting a pipe to said body portion com-
paratively near one of the edges thereof for
10 the purpose of allowing said pipe to fit closely
against the wall of a building, and a cap for
covering said body portion, the arrangement
being such that said cover projects outwardly
15 from the wall.

4. As an article of manufacture, a water-
10 proof entrance-bushing for wires, comprising
a web portion provided with apertures through
which wires may be threaded, means for se-
curing said web portion upon a wall, and a
20 dome-like member connected with said web
and adapted to shelter the same.

5. As an article of manufacture, a water-
25 proof entrance-bushing for wires, comprising
a web provided with ears disposed adjacent
with one of its edges and in alinement with
each other for engaging a wall, a pipe for en-
gaging said web, said pipe disposed compara-
30 tively near one of the edges of said web for
the purpose of allowing said web to project
laterally from the pipe a comparatively great
distance in the opposite direction, and a cap
mounted upon said web and concentric thereto,
35 said cap being adapted to project outwardly

from said wall a comparatively great distance 35
so as to thoroughly protect the wires.

6. As an article of manufacture, a water-
30 proof entrance-bushing for wires, comprising
a web provided with ears integral therewith
whereby the same may be mounted upon a 40
wall, and further provided with apertures and
with means for securing a pipe to said web,
said apertures having rounded surfaces to pre-
vent the abrasion of wires threaded there-
45 through, a cap mounted upon said web, and
means for connecting a pipe to said web inde-
pendently of said ears.

7. As an article of manufacture, a water-
50 proof entrance-bushing for wires, comprising
a body portion provided with apertures, means
for connecting said body portion upon a wall
so that the same will be self-supporting, means
for connecting a pipe to said body portion
55 independently of the support therefor, said
body portion being provided with apertures
through which wires may be threaded, a cap
provided with a lug and fitted upon said body
portion, and a screw engaging said lug and
60 said body portion for holding said cap secured
thereupon.

In testimony whereof I have signed my name
to this specification in the presence of two sub-
scribing witnesses.

WALTER BELL HOPKINS.
